ATTORNEY.

UNITED STATES PATENT OFFICE.

ROBERT R. DUNLOP, OF COLUMBUS, OHIO, ASSIGNOR TO THE JEFFREY MANUFACTURING COMPANY, OF COLUMBUS, OHIO, A CORPORATION OF OHIO.

ELECTRIC CONTROLLER.

1,348,397.

Specification of Letters Patent.

Patented Aug. 3, 1920.

Application filed September 28, 1916. Serial No. 122,709.

To all whom it may concern:

Be it known that I, ROBERT R. DUNLOP, a citizen of the United States, residing at Columbus, in the county of Franklin and 5 the State of Ohio, have invented certain new and useful Improvements in Electric Controllers, of which the following is a specification, reference being had therein to the accompanying drawing.

10 The present invention relates to certain new and useful improvements in electric controllers, and especially to that class of electric controllers which is adapted to control the motors of electric locomotives, traction 15 cars and the like.

As commonly constructed the controlling apparatus of an electric locomotive comprises one or more rotatable cylinders having metallic segments adapted to contact 20 with stationary contact brushes connected with the wiring of the locomotive. These segments are so proportioned and arranged that the rotation of the cylinders will cause the segments to contact with the brushes in 25 such manner that the wires of the locomotive will be connected into circuits through which the electric currents will flow to cause the rotation of the armatures of the motors in the direction and at the speed desired.

30 Whenever such contacts are broken while the current is flowing through them an arc is produced, the intensity of which is proportional to the strength of the current broken. To prevent the destruction of the 35 contact segments and brushes by the arcs formed when heavy currents are broken, magnetic blow out mechanism is provided to extinguish these arcs. The inclusion of magnetic blowouts in a controller materially increases its over all dimensions, and often 40 seriously crowds the space available for the motorman and for other operating mechanism. To keep the controller within the allowable dimensions resort has been had to 45 the expedient of providing an auxiliary, solenoid actuated, contact switch outside the controller, by which the source of electrical supply shall be connected into or disconnected from the circuits of the motors, the 50 contacts in the controller being used only for varying the resistance by which the speed is controlled and for governing the direction of rotation of the armatures.

When such an auxiliary contact switch is 55 used it must be opened before breaking the

connections between any of the contact segments of the controller and their respective brushes if destructive arcing is to be avoided. When the contact switch has been opened it should not be reclosed until after the controller cylinder has been returned to its off position, otherwise there might be an excessive flow of current through the circuits of the motors.

It is the especial object of this invention 65 to provide a master switch device, associated with the operating handle of a controller, whereby a movement of the handle from the off position will cause the closing of an auxiliary switch, and any movement in a reverse direction will cause said switch to open.

It is a further object of this invention to provide such a master switch with means to prevent the reclosing of the auxiliary 75 switch before the return of the controller handle to the off position.

The devices by which I attain these objects are fully set forth in the following specifications and illustrated in the accompanying drawings of which:

Figure 1 is a plan view of my improved master switch device, associated with the handle of a controller, and having part of the casing broken away to show the internal parts.

Fig. 2 is a side elevation of the devices shown in Fig. 1.

Fig. 3 is a cross section taken along the line 3—3 of Fig. 1 showing also the connection with the controller.

Fig. 4 is a section taken along the line 4—4 of Fig. 1.

Fig. 5 is a diagram of the electrical circuits of a single motor locomotive equipped 95 with the devices of my invention.

Fig. 6 is a diagram of the electric circuits of a two-motor locomotive having a controller adapted to connect the motors in series while starting the load and in parallel after the train is under way and which is equipped with the devices of my invention.

Like numerals refer to similar parts in the several figures.

Referring to the drawing the numeral 1 indicates the top plate of a casing having a bearing 2, in which is journaled the spindle 3 of the commutating cylinder of a locomotive controller. Attached to the plate 1, 110

by suitable cap screws 4, is a casting 5 having an upstanding circular flange 6 concentric with the spindle 3. Within the flange 6 is a ring 7, composed of suitable insulating material, upon which is mounted a metallic contact ring 8 having a lug 9 by which it is connected with the conductor R of the locomotive wiring. Fixed to the spindle 3, above the bearing 2, is a hub 10 from which the arm 11 extends radially. The hub 10 is expanded upward at 12 to form a pivot bearing for the handle H, which has a lateral expansion 13 and a depending flange 14, concentric with and overhanging the flange 6, to form a protecting casing for the operative parts of the device. A screw cap 15, threaded to the upper part of the spindle 3, secures the handle H in place.

Attached to the casing 13, is a block 16 of suitable insulating material, to which is secured a metallic block 17 having a contact spring 18 in engagement with the ring 8. Projecting from a cylindrical recess 19 in the block 17 is a plunger 20 adapted to limit longitudinal movement in opposition to the compression spring 21. Formed on the radial arm 11 is an upstanding flange 22 adapted to engagement by the hook 23 which is pivotally connected to the casing 13 by the pin 24 in the depending brackets 25. The hook 23 is provided with an extension 26 which bears upon and slides over the surface of the flange 6. Formed on the upper edge of the flange 6 is a cam 27, so positioned that when the controller cylinder is in its off position the extension 26 will be raised to lift the hook 23 out of engagement with the flange 22 of the radial arm 11.

When the controller cylinder is in the off position, if the handle H be rotated toward the working positions, the plunger 20 will contact with the radial arm 11, forming an electric connection from the conductor R through the controller casing to ground. As the rotation of the handle continues the spring 21 will be compressed until the end of the radial arm 11 is engaged by the lug 28 of the flange 14, when the arm and the controller cylinder with it will be rotated in the direction of the movement of the handle. As this rotation continues the extension 26 of the hook 23 will be moved away from the cam 27 allowing the hook to fall to its lower position. If now the movement of the handle H be reversed the contact between the plunger 20 and the arm 11 will be broken and at the same time the hook 23 will engage the flange 22, after which a reengagement of the arm 11 with the plunger 20 is impossible until the handle has been returned to the off position to disengage the hook 23.

In the diagram shown in Fig. 5 of the drawings, A represents the armature and B 65 the field coil of the motor of a single motor

locomotive which derives electric current from the trolley wire C through the trolley pole D. E is the reverse switch of the controller and need not be further described as it forms no part in the present invention. 70 F represents the commutating cylinder of the controller which is of a type common in the art, rotatable upon its longitudinal axis by means of the handle H. The conductor J extends from the trolley pole D 75 to the controller brush a, and the conductor K extends from the controller brush f through the reverse switch and motor to ground. L denotes the rheostat which is connected with the brushes b, c, d, e, and f of 80 the controller in the usual manner. M indicates an auxiliary switch, connected in the conductor J, and actuated by the solenoid N to make and break the main circuit of the locomotive. P indicates as an entirety the 85 master switch which is included in the branch circuit R with the solenoid N to control the action of the switch M. The position and construction of the master switch P is such that, when the cylinder F is in 90 its off position O, any movement of the handle H will close the circuit R to actuate the solenoid N and close the switch M to allow current to flow to the motor. The further movement of the handle H brings 95 the successive segments of the cylinder F in contact with their respective brushes to cut out the resistance L step by step, in the usual manner, as the speed of the armature increases. A movement of the handle H from 100 any of the operative positions in the direction of the off position will open the master switch P, thereby deenergizing the solenoid N and open the switch M, cutting off all current from the motor circuit, and thus 105 effectively preventing the formation of arcs between the contact segments and brushes of the controller as the cylinder is turned to the off position. If, while a considerable part of the resistance L is cut out of the 110 motor circuit and the armature A is at rest, or its speed materially reduced, the switch M should be reclosed, there would result an abnormal flow of current through the motor which would either damage the apparatus or cause the opening of the circuit breaker at the power house. I prevent the occurrence of such conditions by the peculiar construction of the master switch P by 115 which the reclosing of the circuit R is prevented until the handle H has been restored to the off position.

In Fig. 6 of the drawings is shown diagrammatically, the electric circuits of a locomotive having two motors and a series parallel controller by which the said motors may be connected in series while accelerating the load and in parallel after the train is in motion. In this diagram A' A'' represent the armatures and B' and B'' the field 125 130

coils of the motors respectively. C is the trolley wire from which current is derived through the trolley pole D. E, is the reverse switch of the controller and needs not be further described as it forms no part in the present invention. F represents the commutating cylinder of the controller, which is of a type common in the art, rotatable upon its longitudinal axis by means of the handle H. The conductor J extends from the trolley pole to the controller brush a, and the conductor K extends from the controller brush f through the reverse switch and motors to ground. L denotes the rheostat which is connected with the brushes b, c, d, and f of the controller in the usual manner. The brushes g, h, i, j and k contact with appropriate segments to change the arrangements of the motors from series to parallel and from parallel to series. When the cylinder moves from position 4 to position 5 the circuit must necessarily be opened at brush f and i before g, h, and k contact with their respective segments. 25 This tends to produce serious sparking to overcome which I have formed a gap 8" in the contact ring 8 of the master switch P, which is so positioned that the contact spring 18 will break connection with the ring 8 causing the switch M to open before the brushes f and i lose contact with their respective segments. The width of the gap 8" is such that the spring 18 will restore the circuit through the solenoid N, after 30 the brushes g, h, and k have contacted with their respective segments on the controller cylinder. By this arrangement current is excluded from the controller and motor circuits while the connections of the motors are 35 being changed from series to parallel, and restored thereto after the completion of such change.

What I claim is—

1. In an electric controller, the combination with a rotatable cylinder, of a handle connected to rotate the cylinder and arranged for limited freedom of motion relative thereto, an electric switch actuated by said handle and adapted to be closed by the free movement of the handle in one direction and to be opened by movement of the handle in the reverse direction before said cylinder is moved in either direction, means to lock said switch open, and means operable at the limit of reverse motion of said handle to release said locking means.

2. In an electric controller, the combination with a commutating electric switch, of a handle connected to actuate said commutating switch and arranged for limited freedom of motion relative thereto, a supplemental electric switch actuated by said handle and adapted to be closed by the free movement of said handle in a direction to close said commutating switch and to be

opened by movement of the handle in the reverse direction before said commutating switch is moved in either direction, means to lock said supplemental switch open, and means operable at the limit of reverse motion of the handle to release said locking means. 70

3. In an electric controller, the combination with a rotatable cylinder, of a handle connected to rotate the cylinder and arranged for limited freedom of motion relative thereto, an electric switch carried by said handle and adapted to be closed by the free movement of the handle in one direction and to be opened by the free movement of the handle in the reverse direction before said cylinder is moved in either direction, means to lock the switch open, and means operable at the limit of reverse motion of said handle to release said locking 80 means. 75

4. In an electric controller, the combination with a commutating electric switch, of a handle connected to actuate said commutating switch and arranged for limited freedom of motion relative thereto, a supplemental electric switch actuated by the free movement of said handle and adapted to be closed by movement of the handle in a direction to close said commutating switch 90 and to be opened by movement of said handle in the reverse direction before said commutating switch is moved in either direction, means to lock said supplemental switch open, and means operable at the limit of reverse motion of said handle to release said locking 95 means. 100

5. In an electric controller, the combination of an electrically actuated main break switch and a manually actuated resistance controlling switch, a handle connected to actuate said resistance controlling switch and arranged for limited freedom of motion relative thereto, a supplemental switch actuated by the free movement of said handle and adapted to close the actuating circuit of the electrically actuated switch when said handle is moved in a direction to close the resistance controlling switch, means to open said supplemental switch when said handle is moved in the reverse direction before said resistance controlling switch is moved in either direction, means to lock said switch open, and means operable at the limit of reverse motion of the handle to release said locking 110 means. 115

6. In an electric controller, the combination of an electrically actuated main break switch and a manually actuated resistance controlling switch comprising a rotatable cylinder, a handle connected to rotate the cylinder and arranged for limited freedom of motion relative thereto, a supplemental switch actuated by the free motion of said handle and adapted to close the actuating 125 130

- circuit of the electrically actuated switch when the handle is moved in a direction to close the resistance controlling switch, means to open the supplemental switch 5 when said handle is moved in the reverse direction before said cylinder is moved in either direction, means to lock said switch open, and means operable at the limit of reverse motion of said handle to release said locking means.
- 10 7. In an electric controller, the combination with a rotatable shaft, a handle connected to rotate the shaft and arranged for limited freedom of motion relative thereto, 15 an electric switch actuated by the free motion of said handle and adapted to be closed by motion of the handle in one direction and to be opened by motion of the handle in the reverse direction before said shaft is moved in either direction, means to lock 20 said switch open, and means operable at the limit of reverse motion of the handle to release said locking means.
8. In an electric controller, the combination with a rotatable cylinder, of a handle connected to rotate said cylinder and arranged for limited freedom of motion relative thereto, an electric switch adapted to be actuated by the free movement of said handle before the cylinder is moved in either direction.
- 25 In testimony whereof I affix my signature, in the presence of two witnesses.
